ASSORTING APPARATUS

Filed March 27, 1928

Inventor:
Chester W. Canine.
by Orwig & Hague Atty's.

UNITED STATES PATENT OFFICE

CHESTER W. CANINE, OF CINCINNATI, OHIO

ASSORTING APPARATUS

Application filed March 27, 1928. Serial No. 265,209.

My invention is an improvement in the art of assorting articles through the use of a number of series of tags, in which number of series each tag of the same series is similar to all of the tags of that series but differs from the tags of all of the other series, and tag holding devices which will each receive tags of a certain series and exclude those of different series.

10 The object of my invention is to provide an apparatus of the class described in which the apparatus for receiving the tags is made adjustable so that a comparatively small number of said tag receiving devices may be employed for a large number of tags, and whereby the operator is positively prevented from placing a given tag upon the wrong tag receiving device.

My invention consists in the construction, 20 arrangement and combination of the various parts of the assorting device, whereby the objects contemplated are attained, as herein-after more fully set forth, pointed out in my claims, and illustrated in the accompanying drawings, in which:

Figure 1 shows a front elevation of one of my improved assorting devices with a tag in position therein. The dotted lines show part of the assorting device tilted to one side to 30 permit the assorting bar to swing laterally.

Figure 2 shows a side elevation of same, one of the sockets of one of the assorting bars being broken away to show its construction.

Figure 3 shows an enlarged, vertical, sectional view through the upper part of the adjustable key moving plate; and

Figure 4 shows a front elevation of a tag having a different arrangement of key receiving notches.

40 Referring to the accompanying drawings, I have used the reference numeral 10 to indicate the bracket designed to be permanently secured by means of a bolt 11 to a support 12. The outer end of this bracket is provided with

45 an upright plate 13, pivotally connected at its upper end to the brackets 10 and having a pin 13a fixed to it at one side and extended rearwardly and designed to engage a part of the bracket to limit the swinging movement of the plate. The dotted lines in Figure 1 show this

plate moved laterally. The plate 13 also has two downwardly extended key members 14 and 15, spaced apart from each other. These key members are designed to have formed on them key lugs 16, and in each plate 13 the key lug 16 is arranged in a different position from that of the other plates.

Slidably mounted in guides 17 at the front of the plate 13 is movable key member 18 having a key lug 19 thereon. The top of the key member 18 is formed with teeth 20.

Extended forwardly from the center of the plate 13 is a sleeve 21 formed on the plate 13, and in the outer end of the sleeve 21 is a screw 21a. Pivotally supported on this sleeve 65 is a key adjusting member 22 having at its lower portion a curved surface provided with teeth 23 to mesh with the teeth 20, and having at its top a series of openings 24 arranged concentrically with the sleeve 21, and each of these openings has adjacent to it a letter of the alphabet or other identification mark, as shown in Figure 1. Fixed to the plate 13 is a pin 25 of such size as to readily pass into any one of said openings 24. The proportions 70 of said parts are such that the outward movement of the member 22 is limited by the screw head 21a, to such an extent that the teeth 23 will not move out of mesh with the teeth on the movable key member 18, and this 75 movable key member is held against outward movement at all times by the lugs 17, and against downward movement by its engagement with the upper ends of the key members 14 and 15, as clearly shown in Figure 2. 80

85 Mounted upon the sleeve 21 is a spring 26 normally holding the key adjusting member 22 toward the plate 13. Surrounding the spring 26 is a circular spring housing 27 having a recess therein at 28, designed to permit the housing and the key locking member 22 to which it is attached to move forwardly a limited distance, and above the member 22 is an indicator 29 directly above the pin 25.

90 These parts are so arranged that the operator may by grasping the housing 27 move the member 22 outwardly away from the plate 13 a short distance, and then turn it so that it may be moved to position until any one 95 of the selected letters on the member 22 is in 100

position directly below the indicator 29, and then when it is released, the spring will move it back into position where it will be locked against rotation by the pin 25, and obviously during this turning movement the key member 18 will be moved laterally so that its key lug 19 assumes a different position.

Mounted within the bracket 10 is a rotatable rod 30 projecting below the bracket 10 and having at its lower end two oppositely disposed sockets 31.

I also provide a number of tag supporting bars indicated generally by the reference numeral 32. Their lower ends are shaped to loosely fit into the socket members 31, and they are inclined upwardly and outwardly from the bracket, and their upper ends at 33 are arranged horizontally and are somewhat thicker vertically than the body portions of the bar, as clearly shown in Figure 2. I also preferably provide two small openings 34 in the opposite end portions of this bar to receive cotter pins 35, for holding the tags upon the bar 32 when the bar is removed from its socket 31. The tags are indicated generally by the reference numeral 36 and are preferably substantially rectangular in outline and formed with openings 37 in their centers to loosely fit the enlarged ends 33 of the bars 32. Each tag is preferably provided with a safety pin 38 and also with a key notch 39 at one side edge, and another key notch 40 at the top edge.

In practical use, and assuming that it is desired to provide an assorting apparatus capable of handling ten lots of laundry articles, each lot containing the laundry articles of forty different customers, that is to say four hundred customers for the ten lots, I then provide forty of the brackets 10 and the adjustable and fixed key members thereon. The spacing of the key lug 16 from the bottom edge of the member 15 is different in each one of said members 15 from the spacing of the lugs of any other member 15. In a like manner the spacing of the notches 39 is varied from the bottom of the edges of the corresponding tags 36, so that forty different combinations may be provided by said keys, one for each customer of a given lot, and one lot for each of the ten positions of the key member 19, making a total of four hundred combinations for the ten lots. These forty brackets are preferably arranged adjacent to each other on a support 12.

I then provide four hundred sets of tags and safety pins, each set having a different arrangement of the key notches 39 and 40, and in this connection I usually provide about ten tags for each set. These, of course, are all alike. I also provide four hundred tag supporting bars 32, and place on each of them one set of tags and pins. The operator removes from one of the bars 32 some or all of the tags thereon and places them upon the

different articles of a certain customer's laundry, and the same proceeding is had with all of the other thirty-nine sets of tags in the first lot, hence, there will be four hundred or less articles in said lot. After the laundry articles have passed through the laundry operation, then the forty assorting bars are placed in the sockets 31 of the forty bracket devices. If one lot of tags has the letter "E" on them, as shown in Figure 4, then the operator moves the key moving device 22 to position with the letter "E" directly below the indicator 29. Then the tags with the goods attached thereto are removed one by one from a suitable receptacle in which the tagged finished laundry articles have been placed, and the operator glances at the number on the tag and places it on the bracket having a corresponding number, and on that particular key device the notches 39 and 40 will exactly register with the key lugs 16 and 19, and hence the tag may be slid past the key device on the body of the assorting bar 32.

When all of the tags in that particular lot have been distributed upon the key bars, and this is done after the laundry processes have been finished, then the operator turns the assorting bars on the bolt 30 laterally and rearwardly to the position shown at the right in Figure 2. Then a new set of assorting bars may be placed in position within the adjustable key devices and within the sockets 31.

The entire lot of bars with tags and laundry articles thereon are then ready for the wrapping department. If the bars are removed from the sockets 31, the cotter pins 35 are first placed in position to prevent accidental removal of any tag from the bar. Then the articles are removed from the safety pins and the bars with the tags thereon are ready for use, upon another lot.

Assuming that the second lot has the tags marked with the letter "A", as shown in Figure 1, then the operator sets the key adjusting devices of all the brackets to the position shown in Figure 1, and they stay in that position until all of the second lot is assorted. By this means the operator performing the assorting is enabled to perform a continuous assorting operation and the operator who removes the articles from the assorting bars may also perform a continuous operation.

By means of my improved adjustable key device, it is obvious that there need be, say for instance, only forty of these key devices and their brackets, to accommodate four hundred differently notched tags, there may be as many similarly notched tags as desired. Furthermore, the sliding key members 18 may be all exactly alike and each of the forty stationary key members 14 need have only one key lug 16 thereon, to accommodate four hundred different kinds of tags.

I claim as my invention:

1. In an assorting apparatus, the combination

tion with a support having a socket, of a bar movable with respect to said support and having one end received in said socket and provided with a tag carrying body portion, and a member movable relative to said bar, and provided with a channel normally arranged to permit the passage therethrough of tags over said end onto said body portion, and adjustable means on said member to vary the contour of said channel to prevent the passage across the free end of the bar of all tags except those of a predetermined outline.

2. In an assorting apparatus, the combination of a tag supporting member designed to receive and support tags, and a tag selecting member provided with a channel normally arranged to permit the passage of tags therethrough and upon the tag supporting member, and an adjustable key means on said selecting member to vary the contour of said channel to prevent the entrance into the channel of all tags except those of a predetermined outline.

3. In an apparatus of the class described, the combination of a tag selecting member having a channel through which a tag may be passed, an adjustable key member slidably mounted upon said tag selecting member having a rack carried thereby, a toothed sector pivotally supported in mesh with the rack, and movable to various positions of adjustment and means for locking it in any position of its adjustment.

4. In an apparatus of the class described, the combination of a tag selecting member having a channel through which a tag may be passed, an adjustable key member slidably mounted upon said tag selecting member having a rack carried thereby, a toothed sector pivotally supported in mesh with the rack, and means for moving the toothed sector to various positions of adjustment and for locking it in any position of its adjustment, said tag selecting member having its tag receiving channel open at the bottom, and said tag selecting member being pivoted at its upper end, for the purposes stated.

5. In an assorting apparatus, the combination of a tag supporting member designed to receive and support tags, and a tag selecting member provided with a channel normally arranged to permit the passage of tags therethrough and upon the tag supporting member, key means on said selecting member capable of movement to predetermined positions for varying the contour of said channel to prevent the entrance into the channel of all tags except those of a predetermined contour, and means for fixing said key means in any of its predetermined positions of movement.

CHESTER W. CANINE.
